(57) **CLAIM**

The ornamental design for a foundation block as shown and described.

DESCRIPTION

FIG. 1 is a top perspective view of a foundation block showing our new design;

FIG. 2 is a top plan view thereof;

FIG. 3 is a bottom plan view thereof;

FIG. 4 is a front elevational view thereof, the rear elevational view being a mirror image thereof;

FIG. 5 is a right side elevational view thereof, the left side elevational view being a mirror image thereof;

FIG. 6 is a front sectional view thereof along the line 6-6 of FIG. 5; and,

FIG. 7 is a right side sectional view thereof along the line 7-7 of FIG. 4.

The broken lines depict the sectional view indicators and form no part of the claimed design.

1 Claim, 7 Drawing Sheets
